United States Patent Office.

WILLIAM F. COLLIER, OF WORCESTER, MASSACHUSETTS.

Letters Patent No. 92,939, dated July 27, 1869.

IMPROVEMENT IN CORN-POPPERS.

The Schedule referred to in these Letters Patent and making part of the same.

To all whom it may concern:

Be it known that I, WILLIAM F. COLLIER, of the city and county of Worcester, State of Massachusetts, have invented certain new and useful Improvements in Corn-Poppers; and I do hereby declare the following to be a full, clear, and exact description of the same, due reference being had to the accompanying drawings, forming part of this specification, in which—

Figure 1 is a side view.

Figure 2 is an end view, showing the spring-catch.

Figure 3 is a view of the other end, showing the clamp, &c.

Figures 4 and 5 show some parts hereinafter more particularly to be described.

The same letters indicate the same parts in all.

My invention relates to the common form of popper shown in fig. 1, the body A being made of wire cloth, and its edge secured by a rim, B, of folded sheet-metal, and the cover the same.

To secure this rim, and stiffen and protect the whole, I put a stiff wire through the rim, at b, folding the end down inside, and bend the wire down under the bottom, and up the other end, where it is secured by the clamp C, as in fig. 3, and thence it may pass to the handle.

The clamp C is made with projections, that may be turned and clinched, one of them passing through the lapped rim, and another through the body, lower down, and clinched. The others, receiving the stiffening-wires, are closed over, so as to hold them, thus holding the adjacent parts firmly.

To make the hinge, I bend a piece of wire in the form shown in fig. 4, which enables me to put it through the rim, with one end forming an eye or loop, to receive the cover above, and the other, passing down and through the body, is turned up inside, holding all securely, as shown.

To form a catch, to hold the cover shut, I bend a piece of spring-wire into the form shown at D, fig. 2, the ends passing through the lapped rim, and the wire then passing down enough to give a good spring, and then, up together, are turned into a ring, at d, which serves the double purpose of a catch, to hold the cover, and as a handle, to release it by.

It is evident that the clamp C may be made with a thick body, as C', and the handle made to screw into it, the projections holding the same.

I do not claim putting rims on to poppers; neither putting wires through them, nor guards along the bottom, nor spring-catches, as the latter have been used attached below the rim; but they soon give way, and become useless.

1. I claim the clamp C, for holding the rim, body, wires, and handle, substantially as described.

2. I claim the making the hinge-wire in the form, and applied in the manner shown and described, and both holding the parts together, and making an eye or hinge for the cover.

WM. F. COLLIER.
